UNITED STATES PATENT OFFICE.

JOHN FREDRIC LEHMAN AND JAMES WILLIAM McDANIEL, OF WEST HUNTSVILLE,
ALABAMA; SAID McDANIEL ASSIGNOR TO SAID LEHMAN.

PROTECTOR AND SMASH-PREVENTING MECHANISM FOR LOOMS.

Application filed April 14, 1923. Serial No. 632,068.

To all whom it may concern:

Be it known that we, JOHN FREDRIC LEHMAN and JAMES WILLIAM McDANIEL, citizens of the United States, and residents of 5 West Huntsville, in the county of Madison and State of Alabama, have invented certain new and useful Improvements in Protectors and Smash-Preventing Mechanisms for Looms, of which the following is a specification.

Our invention relates to improvements in looms, dealing particularly with improvements in the mechanism by which a so-called shuttle smash is prevented.

15 An object of the invention is to provide protecting means for a loom which will cause the stopping of the loom immediately upon the happening of any false operation in the throwing of the shuttle whether this 20 false operation consists of the absence of a shuttle in either box, the collision of two shuttles in the warp shed or the presence of a shuttle in each box.

A further object of the invention is to 25 provide a protector mechanism for a loom which operates automatically to stop the loom upon the happening of any of the foregoing occurrences.

A further object of the invention is to 30 provide a protector mechanism for looms which will prevent the damage to the cloth resulting from what is commonly known as a "two shuttle smash" by causing the stopping of the loom under such a condition in 35 which two shuttles are likely to be thrown through the warp shed from opposite ends of the lay beam.

Other objects and advantages will appear in the following specification, reference being had to the accompanying drawings, in which:

Fig. 1 is an end elevation of only so much of a loom as is necessary to illustrate the application of the improved protector mechanism,

45 Fig. 2 is a detail end elevation showing the lay beam thrown forward to the other extremity of its movement from the position shown in Fig. 1,

50 Fig. 3 is a detail perspective view of the lay beam showing the protector mechanism applied,

Fig. 4 is an inverted perspective view illustrating the same position of parts in

Fig. 3 but clearly showing the particular 55 positions of the various cams, and

Fig. 5 is a detail plan view illustrating the relation of the knock-off or bunter lever to the shipper handle.

The construction necessarily involves some 60 of the mechanism of the loom, but as stated before, only so much of a loom is shown in the drawings as is necessary to illustrate the method of application and working of the invention. The loom frame 1 carries a 65 shaft 2 which is to be considered the shaft by which the loom is driven. This shaft carries two pulleys 3 and 4 (Fig. 5), the first being fast on the shaft, the other being loose.

A belt 5 is shown applied to the fast pulley 3. This belt is adapted to be shifted over onto the loose pulley 4 when it becomes necessary to stop the loom as for example in the event of a shuttle smash. The fork 6 75 of a shipper arm 7 partly embraces the belt 5 so as to be able to shift the belt over onto the pulley 4 when the arm is moved toward the left (Fig. 5). The shipper arm may be part of the shipper handle 8. The actual 80 construction in practice may be different but the principle of operation remains the same. The shipper handle 8 rests in a recess 9 (Fig. 5) when the loom is running. The recess has communication with a slot 10 in 85 a bracket 11 which is fastened adjacent to one end of the breast beam 12. The breast beam is situated at the front of the loom. A spring 13 tends to pull the handle 8 toward the left, and the tension of the spring 90 is useful in keeping the handle seated in the recess 9 during the operation of the loom.

A knock-off or bunter lever 14 (Fig. 5) is adapted to unseat the shipper handle 8 95 from the recess 9 and thereby permit the spring 13 to pull the handle toward the left and cause the fork 6 to shift the belt 5 onto the loose pulley 4. The lever 14 is pivoted at 15 beneath the breast beam. 100 The right end of the lever terminates in a head 16 which has a V-shaped groove 17 along the edge placing the lay beam 18. All of these parts are common in looms as now constructed with the exception of 105 the particular construction of the head 16 of the bunter lever. The V-groove 17 is provided for the particular purpose of re-

ceiving the point of the daggers 19 and 20 which, also, are parts of the invention.

The lay beam 18 is carried by arms 21 which are mounted on a pivot shaft 22 (Fig. 1) so that the lay beam may be swung back and forth between the positions in Figs. 1 and 2 by means of the crank 23 and connecting rod 24. The connecting rod joins the wrist pin of the crank with a pivot pin 25 situated at the back of the lay beam. The shuttle 26 travels from side to side of the loom on the lay beam 18, being thrown from one end of the lay beam to the other by the usual picker-sticks 27, of which only 1 is shown in Figs. 1 and 2 of the drawings merely for the purpose of giving an idea as to where they are located.

The shuttle 26 operates in front of the reed 28 which is situated between the lay beam and the hand rail 29. The warp threads 30 are manipulated by a suitable harness 31, and the shuttle 26 is thrown through the shed of the warp in order to insert the weft or filling in accordance with the customary manner. It is the picker-sticks which throw the shuttle from side to side as described to accomplish this purpose. The shuttle is thrown from one shuttle box 32, at one end of the lay beam, to another shuttle box 33 at the opposite end of the lay beam.

Shuttle boxes are made differently in various types of looms. They are often made to accommodate more than one shuttle. The present illustration is confined to showing only one shuttle box at each end of the lay beam, the principle of operation of the invention being identical regardless of the number of shuttle boxes which might be present in a loom.

Binders 34 and 35 in the respective shuttle boxes serve to hold the shuttle in place when received. The binders are pivoted at 36 (Fig. 3) and are pressed inward by springs 37. The presence of a shuttle in a particular box (32 for example) presses the binder 34 out against the tension of the spring 37.

Mounted in a series of bearings 38, 39, 40 and 41 beneath the lay beam 18 is a pair of cam shafts 42 and 43. These are in axial alinement. They are adapted to turn separately but are also adapted to turn in unison in the event that each of the shuttle boxes 32 and 33 is occupied by a shuttle. The separate turning occurs when only one of the boxes is occupied by a shuttle.

These actions are performed by binder fingers 44 and 45 which are carried by the respective shafts 42 and 43 and bear against the binders 34 and 35. Figs. 2, 3 and 4 show the cam shafts 42 as having been turned by the outward pressing of

the binder 34 by the shuttle 26 in the box 32. The respective shafts 42 and 43 have pairs of cams 46, 47 and 48, 49. By virtue of their functions, the adjacent cams 47 and 48 are called depressor cams, while the cams 46 and 49 are called release cams.

In each instance, the pairs of cams are approximately 90° apart on the respective shafts. The cams 46 and 49 are situated beneath rockers 50 and 51 which are fixed at the ends of a dagger shaft 52. This shaft is supported in bearings 53 beneath the lay beam 18. The turning of the cam shaft 42 by virtue of the displacement of the binder 34 (Fig. 3) causes the release cam 46 to depart from the rocker 50. The same turning of the shaft causes the depressor cam 47 to ride up under the flange 54 of the dagger 19 and cause the depression thereof into a position corresponding with that of the dagger 20. Both daggers will therefore pass beneath the head 16 of the bunter lever 14 on the forward motion of the lay beam. This is illustrated in Fig. 2.

The flange 54 of the dagger 19 carries a wedge 55 on the underside with which the depressor cam 47 contacts in the action just described. The other depressor cam 48 is also adapted to contact with this wedge. Such contact occurs when the binder finger 45 on the right end is displaced and the cam shaft 43 is turned as a consequence. A spring 56 connected between the dagger 19 and a suitable mounting on the lay beam 18, tends to hold the dagger up and the wedge 55 in contact with one or both of the depressor cams 47 and 48. A spring 57, connected between the rocker 51 and a suitable mounting on the lay beam tends to rock the dagger shaft 52 so as to keep the rockers 50 and 51 in contact with the release cams 46 and 49.

The dagger 19 is loose on the shaft 52 and is depressed each time either the shaft 42 or 43 is turned. The flange 54, and consequently the wedge 55, is broad enough to cover both depressor cams 47 and 48 so that the depressing action of the dagger may be performed. The dagger 20 is fixed on the shaft 52. It always occupies a normally depressed position (Fig. 1) and rises to a position where it might engage the head 16 of the bunter lever 14 only when both binder fingers 44 and 45 are pressed outward by the presence of a shuttle in each box. The raising of the dagger 20 therefore happens only when both release cams 46 and 49 are depressed and the spring 57 is permitted to rock the rockers 50 and 51 into contact with said cams.

The operation may now be reviewed to advantage. The loom runs as long as the belt 5 (Fig. 5) is on the fast pulley 3. The shaft 2 drives the loom and ultimately causes the turning of the crank 23 (Fig. 1) by

means of which the lay beam 18 is rocked back and forth on its pivot 22 through the connecting rod 24. The shuttle 26 is thrown from one box 32 to the other 33 by means of picker sticks 27 of which one only is shown in Figs. 1 and 2. The shuttle is thrown through the shed of the warp while the lay beam 18 is in the rear position, thus giving ample time for the transit of the shuttle 10 while the warp is fully opened.

It often happens in looms which use a plurality of shuttles for inserting various colors of filling, that a collision of the shuttles will occur somewhere along the lay 15 beam. This is commonly called a shuttle smash. This causes the destruction of a part of the warp and also injures one or both of the shuttles.

Should it so happen that both shuttle 20 boxes 32 and 33 are vacant, as would be the case in the event of such shuttle smash, both binders 34 and 35 would be moved inward, permitting both binder fingers 44 and 45 to follow. The binder fingers are kept in 25 contact with the respective binders by springs 56 and 57. This causes both cams 47 and 48 to turn rearwardly, permitting the spring 56' to raise the dagger 19 into the position where it would engage the groove 30 17 of the head 16 and swing the bunter lever 14 (Fig. 5) to release the shipper handle 8 from the recess 9.

This action is suggested by the arrow *a* in Fig. 1 and also by the dotted line position 35 in Fig. 2, although neither of these views is intended to illustrate the positions of the parts in a two-shuttle smash. The turning of the cam shafts 42 and 43 does not affect the position of the dagger 20. The points 40 of the release cams 46 and 49 simply ride beneath the rockers 50 and 51, holding the latter up and the dagger 20 down. It is only the dagger 19 which becomes operative to engage the head 16 of the bunter lever 14 and thereby stop the loom in the event of a 45 two-shuttle smash.

It has been explained how the shuttle 26 makes the transit across the lay beam 18 before the lay beam reaches the forward position in Fig. 2. Assuming the shuttle 26 to be in the box 32 at the left in Fig. 3, it is necessary that the shuttle be thrown across to the box 33 before the lay beam 18 assumes the position in Fig. 2. The presence of the 55 shuttle in either box 32 or 33 will cause the turning of either cam shaft 42 or 43 so that one or the other of the depressor cams 47 and 48 depresses the dagger 19 down into the normal plane of the dagger 20. This is 60 shown in full lines in Fig. 2. It is in this position that the head 16 of the bunter lever 14 is avoided.

However, assume that instead of the shuttle 26 being thrown across to the box 33, it 65 is thrown completely off of the lay beam so

that it fails to reach the box 33. Both binder fingers 44 and 45 are therefore rocked inwardly (as in the case of the two-shuttle smash), both cams 47 and 48 are correspondingly turned, permitting the spring 56' to 70 raise the dagger 19 into a position where it will engage the head 16 of the bunter lever and thus stop the loom.

Assume each of the shuttle boxes 32 and 33 to have a shuttle therein. This should 75 not be, because the throwing of one of the shuttles would cause a smash as described before. The presence of a shuttle in each box will displace the binders 34 and 35 so that both cam shafts 42 and 43 are rocked 80 outward. Both release cams 46 and 49 therefore move forward and downward toward the observer in Fig. 3. The spring 57' causes the shaft 52 to turn so that the rockers 50 and 51 both follow the cams, 85 thereby causing the dagger 20 to rise to a position corresponding with that shown in Fig. 1 and this dagger then being in position to move in the direction of the arrow *a*, will engage the head 16 at the groove 17, 90 cause the bunter lever 14 to rock in the direction of the arrow in Fig. 5. The shipper handle 8 is released from the recess 9, and the spring 13 causes the shipper handle to move over in the slot 10 so that the fork 6 95 transfers the belt 5 onto the loose pulley 4.

While the construction and arrangement of the improved protector mechanism as herein described and claimed is that of a generally preferred form, obviously modifications and changes may be made without departing from the spirit of the invention or the scope of the claims.

We claim:

1. A lay having two cam shafts each provided with a finger, binders with which each of the fingers coacts, a dagger shaft provided with a pair of daggers, and means carried by the various shafts adapted to hold one dagger in an inoperative position and alternately move the other dagger into a corresponding inoperative position.

2. A lay having two cam shafts each provided with a finger, binders with which each of the fingers coacts, a dagger shaft, a pair of daggers carried by the dagger shaft, means on each cam shaft adapted to keep one dagger in an inoperative position, means on the dagger shaft with which said means cooperate to perform the foregoing function, and means carried by the cam shafts adapted to alternately act to place the other dagger in an inoperative position.

3. A lay having two cam shafts each provided with a finger, binders with which each of the fingers coacts, a dagger shaft, a pair of daggers carried by said shaft, rockers carried by the dagger shaft, means on the cam shafts adapted to engage the rockers to hold one dagger in an inoperative posi- 130

tion but also being adapted to simultaneously move away from the rockers to permit said daggers to move to an operative position, and means carried by both cam shafts being then adapted to move the other dagger to an inoperative position.

4. A lay having two cam shafts each provided with a finger, binders with which each of the fingers coacts, a dagger shaft, a pair of daggers carried by said shaft, a pair of rockers carried by said shaft, cams carried by each cam shaft adapted to engage the respective rockers and thereby hold one of the daggers in an inoperative position, said cams also being adapted to engage the rockers alternately corresponding with rocking movements of the cam shafts but still maintain said dagger in said inoperative position, and other cams carried by the respective cam shafts being adapted to move the other dagger into an inoperative position at each forward movement of one or both of the cam shafts.

5. In a loom having a lay, shuttle boxes and binders; two shafts each provided with a finger to coact with an adjacent binder, a pair of daggers mounted independently of the shafts, means associated with each shaft and one of the daggers for keeping said dagger depressed in an inoperative position as long as the binders are pressed outward alternately in the proper operation of the loom and by means of which said dagger is permitted to rise to an operative position when both binders are pressed outward in an improper operation of the loom, and means associated with said shafts and the other dagger by means of which said dagger is caused to be depressed to an inoperative position when the binders are pressed outward alternately in the proper operation of the loom, said dagger also being depressed when both binders are pressed outward but which is caused to rise to an operative position when both binders are pressed inward in an improper operation of the loom.

6. A loom having a lay, shuttle boxes and binders; two shafts each having a finger, a binder adjacent to each finger, a pair of daggers mounted independently of said shafts, means on both shafts adapted to hold one dagger in a depressed position, and means also on said shafts adapted to move the other dagger alternately during the operation of the loom.

7. In a loom, knock-off mechanism combined with the lay of the loom comprising two shafts each with a finger, binders with which each of the fingers coacts, a pair of daggers mounted independently of the shafts, means carried by each shaft and being alternately movable therewith adapted to maintain one of the daggers in an inoperative position while the loom is in operation, and other means carried by said

shafts operating alternately with said shafts and being adapted to cause alternate depressions of the other dagger to an inoperative position while the loom is in operation.

8. In a loom, a knock-off mechanism combined with the lay, comprising two shafts, a pair of daggers, means by which the daggers are mounted independently of said shafts one dagger being fixed to said means the other being loose thereon, means carried by each shaft and by the dagger mounting means to maintain the fixed dagger in an inoperative position during alternate turnings of the shafts, and means carried by each shaft adapted to move the other dagger to an inoperative position at each of said alternate turnings.

9. In a loom, a knock-off mechanism combined with the lay having two shafts each with a finger, binders with which each coacts, a pair of daggers, means by which they are carried independently of said shafts, means on each of the shafts coacting with means on said carrying means to keep one of the daggers in an inoperative position during all movements of the shafts excepting a concerted movement of said shafts in a predetermined direction, means carried by both shafts adapted to move the other dagger into an inoperative position at all movements of said shafts excepting a concerted movement in the opposite direction, and means on said carrying means extending within reach and contact of both of the last moving means to support said other dagger in said inoperative position.

10. In a loom, a knock-off mechanism combined with a lay having two shafts each with a finger, binders with which each finger coacts, a dagger shaft supported independently of said shafts, a pair of daggers carried by said shafts one being fixed thereon the other being loose, a rocker at each end of the dagger shaft, cams on the shafts each coacting with a rocker and being adapted to maintain the fixed dagger in an inoperative position while the other cam departs from the other rocker in a movement of the corresponding shaft by virtue of a displacement of the corresponding finger, means tending to keep said rockers in engagement with said cams, other cams on said shafts coacting with the loose dagger, a flange carried by said dagger having a wedge broad enough to cover both cams so that the loose dagger may be moved to an inoperative position upon a certain movement of either of said shafts, means tending to hold said shafts against said movement, and means tending to keep said wedge in engagement with said last cams.

JOHN FREDRIC LEHMAN.
JAMES WILLIAM McDANIEL
